Des. 212,233

Patented Sept. 17, 1968

212,233

PLUG-IN POWER SUPPLY

Joseph A. Mas, Woodbury, N.Y., assignor to Dynamics
Instrument Corporation, Plainview, N.Y., a corpora-
tion of New York

Filed Feb. 23, 1968, Ser. No. 10,689

Term of patent 14 years

(Cl. D26—15)

FIGURE 1 is a perspective view of the plug-in power supply in accordance with the invention.

FIGURE 2 is a plan view of the power supply shown in FIGURE 1.

FIGURE 3 is a bottom view of the power supply known in FIGURE 1.

FIGURE 4 is one end view of the power supply shown in FIGURE 1.

FIGURE 5 is a side view of the power supply shown in FIGURE 1.

FIGURE 6 is another end view of the power supply shown in FIGURE 1.

I claim:

The ornamental design for a plug-in power supply, as shown.
